Primary Examiner — John Windmuller*Assistant Examiner* — Melvin L Davis(74) *Attorney, Agent, or Firm* — Sheridan Ross PC(57) **CLAIM**

The ornamental design for a schedule rack, as shown and described.

DESCRIPTION

FIG. 1 is a perspective view of the schedule rack;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines depict portions of the schedule rack in which the design is embodied that are not considered part of the claimed design.
